UNITED STATES PATENT OFFICE.

REGINALD G. STANDERWICK, OF MARBLEHEAD, MASSACHUSETTS, ASSIGNOR TO
GENERAL ELECTRIC COMPANY, A CORPORATION OF NEW YORK.

TURBINE-REGULATING MEANS.

Application filed April 20, 1927. Serial No. 185,327.

The present invention relates to elastic fluid turbine installations wherein the turbine is controlled by some operating conditions not concerned directly with the driven load of the turbine and hence not responsive to the speed of the turbine. In such installations, it is the practice to utilize the turbine for driving an alternating current machine connected to main bus bars to which are connected another alternating current machine or machines which are controlled to fix the frequency of the system. The speed of the turbine, therefore, is fixed by the frequency of the system. In this manner, it may be utilized to carry more or less load in response to any desired operating condition.

In turbine installations of this type, it is important that the arrangement be such that the turbine cannot continue to take on load to an extent such that the alternating current machine which it drives is overloaded, and one object of my invention is to provide an improved arrangement to guard against this, the arrangement being such that while it permits the alternating current machine to be loaded to capacity, prevents it from being overloaded.

In connection with turbines of this type, it is the practice to provide, in addition to the control means above referred to, a speed governor which is set for a speed somewhat higher than that at which the turbine runs when tied in on the line with other machines. With this arrangement, the speed governor is normally out of action and only comes into action to take control of the turbine in case the speed exceeds a predetermined high value. Such governors are termed pre-emergency governors because they are set to come into action in advance of the emergency governor. A further object of my invention is to provide an improved arrangement whereby the pre-emergency governor or speed governor takes control of the turbine when certain abnormal operating conditions are met with.

An application of my invention is in connection with the utilization of elastic fluid from some preferred source of supply, such as waste heat boilers, for example, where it is desired to utilize in the turbine all the elastic fluid available from such preferred source of supply, and a further object of my invention is to provide an improved control arrangement for use in connection with a turbine

utilizing elastic fluid from a preferred source of supply.

For a consideration of what I believe to be novel and my invention, attention is directed to the accompanying description and the claims appended thereto.

In the drawing, Fig. 1 is a diagrammatic view of an elastic fluid turbine equipped with regulating means embodying my invention, and Fig. 2 is a similar view of another application of my invention.

Referring to the drawing, Fig. 1, 1 indicates an elastic fluid turbine having an admission conduit 2 and exhaust conduit 3. Turbine 1 may be of any suitable type. In the present instance I have illustrated an impulse turbine of what is known as the extraction type, a conduit 4 being provided at an intermediate point in the turbine for extracting lower pressure elastic fluid for industrial or process purposes. 5 indicates a valve in conduit 4 provided with an operating arm 6 connected by a link 7 to a movable abutment 8. Movable abutment 8 is subjected to the pressure in conduit 4 through a conduit 9. The arrangement is such that movable abutment 8 serves to operate valve 5 to maintain substantially constant pressure in conduit 4 beyond valve 5. The arrangement of extraction turbine illustrated is diagrammatic and wholly by way of example. It is intended to represent any suitable extraction type machine. A known type which I may utilize in actual practice is one such as that shown in the patent to Norton, 1,091,078, dated March 24, 1914.

The valve means for controlling the flow of elastic fluid to turbine 1 is indicated at 10. It is here shown diagrammatically and by way of example as comprising a single valve member connected by a stem 11 to a lever 12 pivoted on a fulcrum 13, the free end of lever 12 being provided with a roller 14 which is engaged by a cam 15 carried by a cam shaft 16. It is to be understood that this valve structure is intended to represent any suitable turbine valve gear. On the end of cam shaft 16 is a pinion 17 which meshes with a rack 18 on the upper end of a rod 19. Rod 19 is connected to a piston 20 located in a cylinder 21. Piston 20 is biased toward the lower end of the cylinder by a spring 21a. When piston 20 moves upward in the cylinder, cam shaft 16 is turned in a direction to open valve means 10, while when the piston 110

moves downward in cylinder 21, cam shaft 16 is turned in a direction to permit valve means 10 to move toward closed position.

Turbine 1 is shown as being direct connected to an alternating current generator 22 connected by lead wires 23 to the main bus bars 24 of an alternating current system of distribution. Connection to bus bars 24 are one or more other alternating current generators, the connections for one of them being indicated at 25. In connections 23 is a suitable circuit breaker 26 and in connections 25 is a suitable circuit breaker 27. Each of these circuit breakers comprises, in addition to the usual blades for opening the line wires, an additional blade 28 adapted when the switch is closed to bridge a pair of contacts 29. When circuit breakers 26 or 27 are opened, blades 28 move from engagement with contacts 29.

At the central portion of the drawing, 30 indicates the oil tank for the turbine, 31 indicates the oil pump which supplies oil under pressure for lubricating the turbine and also for supplying pressure to actuate the valve mechanism, and 32 indicates the oil strainer for pump 31. Pump 31 is provided with a vertical shaft on the upper end of which is a worm wheel 33 driven by a worm 34 on the end of the turbine shaft 35. Also driven by the vertical pump shaft is a suitable speed governor 36.

The parts just described are not shown in correct relation to the turbine 1, but are shown diagrammatically and as having been brought around into the plane of the paper. This is for the purpose of showing diagrammatically the connections of the parts of the regulating mechanism to each other. As will be understood by those familiar with elastic fluid turbines, the parts will be suitably arranged in combination with the turbine in a usual and convenient manner. It will be understood, also, that the relative sizes of the parts are not correctly shown, the size of some of the parts being greatly exaggerated for purposes of illustration.

Speed governor 36 has its weight arms 37 connected by a stem 38 to a pilot valve 39 provided with upper and lower valve heads 40 and 41. Stem 38 is preferably connected directly to pilot valve 39 so that the pilot valve rotates with the speed governor. When weights 37 fly outward, pilot valve 39 is pulled downward, while when they move inward, pilot valve 39 is moved upward.

Surrounding pilot valve 39 is a pilot valve bushing 42 provided with annular grooves 43 and 44 controlled by valve heads 40 and 41 and with passages 45. Surrounding bushing 42 is a pilot valve casing 46 provided with three spaced annular grooves with which grooves 43 and 44 and passages 45 respectively communicate. Bushing 42 can move axially in casing 46 but cannot

turn therein, being held from turning by a suitable spline (not shown). The upper annular groove in casing 46 is connected by a pipe 47 to a pilot valve casing 48; the middle annular groove is connected by a pipe 49 to cylinder 21 beneath piston 20; and the lower annular groove communicates directly with oil tank 30. Pilot valve bushing 42 is connected by a stem 50 to a lever 51 mounted on a fulcrum 52. Stem 50 is shown as being constructed in two parts united by a long nut 53 having threads in its bore and gear teeth on its outer surface. The upper part of stem 50 is pivotally connected to the upper end of nut 53 and the lower part of stem 50 is threaded and engages with the threads in nut 53. Meshing with the gear teeth on nut 53 is a gear wheel 54 connected by bevel gear wheels 55 to a synchronizing motor 56. In these connections is a friction clutch 56^a of suitable construction through which motor 56 drives nut 53. The total movement of pilot valve bushing 42 is limited by a pin 56^b which engages stops 56^c. When pin 56^b engages a stop 56^c, clutch 56^a slips so as to avoid stalling of the motor. When motor 56 turns in one direction, nut 53 is turned to shorten the length of stem 50, while when motor 56 turns in the opposite direction, nut 53 is turned to increase the length of stem 50, thereby raising and lowering pilot valve bushing 42. This diagrammatic showing of motor 56 in connection with stem 50 is intended to represent any suitable synchronizing arrangement. In particular, I may use an arrangement such as that disclosed in the patent to Scott, 1,584,610, patented May 4, 1926.

The left hand end of lever 51 is connected by a link 57 to one end of a lever 58, pivoted on a fulcrum 58^a. The other end of lever 58 is connected to rod 19. The right hand end of lever 51 is pivotally connected to one end of a floating lever 59. The other end of floating lever 59 is connected by a stem 59^a to a pilot valve 60 located in pilot valve casing 48. Pilot valve 60 has two valve heads 61 and 62. Valve head 61 cooperates with an annular groove 63 in pilot valve casing 48 and valve head 62 cooperates with an annular groove 64 in the pilot valve casing. Connected to annular groove 63 is a pipe line 65 which communicates with the discharge side of pump 31. 66 is a suitable non-return valve arranged in this pipe line and 67 is a pressure relief valve which may be set to relieve the pressure on the discharge side of pump 31 whenever it exceeds a predetermined high value. Annular groove 64 may communicate with any suitable discharge region. Lever 59 is connected by a link 68 to the central portion of a lever 69. The right hand end of lever 69 is pivotally connected to a stem 70 which at 130

- its lower end carries a piston 71 which moves in a cylinder 72. On stem 70 is a threaded portion 73 on which is an adjustable bushing 74. Mounted on bushing 74 in 5 a manner such that the bushing may turn in it is a spring clamp 75 to which is attached one end of a spring 76, the other end of the spring being attached to a spring clamp 76^a fixed in the top of cylinder 72. Spring 10 76 serves to oppose upward movement of piston 71 and may be adjusted to load the piston to the desired extent.
- 77 indicates a plurality of waste heat boilers, it being understood that by the term 15 waste heat boilers, I mean boilers which utilize for vaporizing water some source of waste heat or some source of waste fuel. That is to say, heat or fuel which if it were not utilized in the boilers would go to waste.
- 20 Boilers 77 discharge elastic fluid into a header 78 from which elastic fluid is supplied to turbine 1 by a conduit 79. Header 78 is connected by a pipe 80 to cylinder 72 beneath piston 7.
- 25 Moved by stem 70 is a contact plate 81 adapted to bridge a pair of contacts 82. 83 indicates a contact-making ammeter having a movable contact arm 84 adapted to engage either of two contacts 85 or 86, 30 or to stand in a position intermediate between contacts 85 and 86. 87 indicates the winding of contact-making ammeter 83. This winding is connected by conductors 88 to line wires 23 of generator 22, the connection being made through a suitable current transformer 89. With this arrangement, the current flowing through ammeter winding 87 is proportional to the load on generator 22. In conductors 88 is a load- 35 adjusting resistance 90.
- 40 Lever 69 is provided at its left hand end with what is termed a magnetic fulcrum, the same being shown diagrammatically as comprising a core 91 arranged in a winding 92 and adapted to engage a stop 93. Connected to lever 69 is a spring 94 which opposes the pull of winding 92 on core 91. When winding 92 is energized, core 91, having been moved to the position shown in the drawing, will be held there by the winding. When winding 92 is deenergized, spring 94 will move the left hand end of lever 69 upward. When this occurs, it must be moved back again manually in order to restore the 45 parts to their former positions. The pull of winding 92 when energized, while sufficient to hold the core in the position shown in the drawing, is not sufficient to move the core to such position after it has been moved 50 away by spring 94.
- 55 95 and 96 indicate the two field windings of synchronizing motor 56. Winding 95, when energized, operates motor 56 in a direction to raise bushing 42 and winding 96, 60 when energized, operates motor 56 in a direction to lower bushing 42. 97 indicates a switch for connecting the field windings of motor 56 either for automatic control or for hand control by means of a hand switch 98. 99 indicates a source of potential for 70 operating motor 56.
- In the drawing, the parts are shown in 75 positions they occupy when the turbine is running at less than full speed, valve means 10 being partially open, and generator 22 being partially loaded. Elastic fluid of the desired pressure is supplied to turbine 1 from waste heat boilers 77. This pressure holds piston 71 in a certain position. Since generator 22 is only partially loaded, the 80 contact lever 84 of ammeter 83 stands in engagement with contact 85. The speed of the turbo-generator set comprising turbine 1 and generator 22 is set by the frequency of the main bus bars 24 which frequency in 85 turn is controlled by other turbo-generators as indicated by the lead wires 25. Speed governor 36 is set for a speed a certain amount higher than that of the turbine so that it is out of action, that is to say, it is 90 in a position such that it does not obstruct the flow of oil through groove 43. As before stated, it forms what is termed usually in this art a pre-emergency governor, being a speed governor which comes into operation 95 at a speed just lower than that for which the usual emergency governor for the turbine is set. Pilot valve 60 is in actual control of the flow of fluid pressure to cylinder 21 beneath piston 20. As shown the pilot valve 100 heads 61 and 62 are positioned so as to prevent either the flow of fluid from conduit 65 past pilot valve head 61 to cylinder 21 or from cylinder 21 past pilot valve head 62 to discharge.
- 104 With switch 97 in the position shown, winding 92 of the magnetic fulcrum is in a circuit which may be traced as follows: Lower line wire 99, conductor 100, conductor 101, switch blade 28 of circuit breaker 27, 110 conductor 102, switch blade 28 of circuit breaker 26, conductor 103, conductor 104, winding 92, conductor 105, conductor 106, and switch 97 to the upper line wire 99. Winding 92 is thus energized so that the 115 magnetic fulcrum is held in the fixed position shown.
- If the pressure in header 78 increases, piston 71 is moved upward somewhat in cylinder 72. This lifts the right hand end of 120 lever 69 and through link 68 lifts the right hand end of lever 59, thus raising pilot valve 60. Fluid pressure now flows from pipe line 65 past pilot valve head 61 through pipe 47, annular chamber 43, passages 45, and pipe 49 to cylinder 21 beneath piston 20 thereby raising piston 20 to open further valve means 10 so as to admit elastic fluid more rapidly to turbine 1. When piston 20 moves upward it turns lever 58 on its ful-
- 125

erum, lowering the right hand end of lever 58 and raising the right hand end of lever 51. This turns lever 59 on link 68 as a pivot, the right hand end of lever 59 being lowered and thereby restoring pilot valve 60 to its former position. On the other hand, if the pressure in header 78 decreases, then piston 71 will move downward in cylinder 72 and, in a manner similar to that already described, effects a closing of valve means 10. Thus the arrangement tends to maintain the pressure in header 78 substantially constant. As a result, valve means 10 will be operated to maintain it in a position such that turbine 1 will utilize all the elastic fluid available from the waste heat boilers, it being understood that variations in pressure in header 78 serve as a guide to the elastic fluid available, the pressure increasing and decreasing as the supply available increases and decreases.

When the turbine is not running, line switch 26 is open so that generator 22 is disconnected from the main bus bars. As a result, the winding 92 of the magnetic fulcrum is deenergized so that the left hand end of lever 69 is in its uppermost position. This holds pilot valve 60 in its uppermost position, permitting free passage of oil from pipe 65 through pilot valve casing 48 to pipe 47. Pressure piston 71 is thus inoperative to perform any regulating of the turbine valve means. Also, at this time, pilot valve bushing 42 will be in a position such that valve heads 40 and 41 cover passages 43 and 44. To start the turbine, switch 97 is moved to its left hand position into engagement with contacts 107, after which hand switch 98 is moved into engagement with its right hand contact thereby closing the circuit on field winding 96. This serves to operate motor 56 in a direction to move pilot valve bushing 42 downward, thus admitting oil to the underside of piston 20. Piston 20 is thus moved upward to open valve means 10 and admit elastic fluid to the turbine. The synchronizing motor is operated gradually by the hand switch 98 until the turbine is up to speed. Line switch 26 is then closed, thereby connecting generator 22 to the main bus bars 24. The speed of the turbo-generator set is then fixed by the frequency of the current in the main bus bars 24 and will be held constant independently of the speed governor. Switch 97 is now moved to the position shown in the drawing after which the left hand end of lever 69 is lowered gradually, bringing plunger 91 inside winding 92, which winding became energized when line switch 26 was closed. The lowering of the left hand end of the lever 69 serves to lower pilot valve bushing 42, and at the same time lower also pilot valve 60. When lever 69 is fully lowered, control of the turbine will

have been taken away from pilot valve bushing 42 and placed under control of pilot valve 60. The position of valve means 10 will now be fixed by pressure piston 71 after the manner already explained.

70

If at any time the switch 27 or the switch 26 opens thereby moving a connector 28 away from contacts 29, the circuit through solenoid 92 will be opened. This releases the magnetic fulcrum, spring 92 raising the left hand end of lever 69. As a result, pilot valve 60 is raised to its uppermost position, thereby taking control of the turbine away from piston 71 and pilot valve 60 and placing it under control of speed governor 36. In this connection, it will be understood that when pilot valve 60 moves upwardly, oil will be admitted under piston 20 to open valve means 10 an amount sufficient to bring the speed of turbine 1 up to a value such that speed governor 36 comes into action to take control of the turbine, the speed of the turbine no longer being fixed by the line frequency. The turbine will then operate under control of the speed governor until normal conditions are restored and the left hand end of lever 69 is again moved downward to bring core 91 into winding 92.

If the supply of elastic fluid from the waste heat boilers increases to an extent such that generator 22 tends to become overloaded, then winding 87 of ammeter 83 will be energized to an extent such as to move contact arm 84 up into engagement with contact 86. This closes a circuit on field winding 95 of motor 56 which may be traced as follows: upper supply line 99, right hand switch blade 97, conductor 106, conductor 108, contact arm 84, conductor 109, conductor 110, field winding 95, and conductor 111 back to the lower supply line 99. Motor 56 then operates in a direction to raise pilot valve bushing 42 to bring it to a position such that the upper edge of annular groove 44 comes above the top edge of head 41, and annular groove 43 is entirely covered by head 40. This permits oil to escape from beneath piston 20 and valve means 10 to close somewhat thus reducing the amount of elastic fluid supplied to the turbine. This decreases the load carried by the set, whereupon contact arm 84 will move away from contact 86.

The fact that generator 22 tended to take more than full load indicated an excess supply of waste heat elastic fluid and with a closing of valve means 10 the pressure of the waste heat elastic fluid will reach its maximum value bringing contact plate 81 into engagement with contacts 82. Now, when contact arm 84 engages contact 85 a circuit will be closed on motor field 96 which may be traced as follows: upper supply line 99, conductor 106, conductor 108, contact arm 84, contacts 82, conductor 112, conductor

113, motor field 96, and conductor 111 to lower supply line 99. Motor 56 is then operated in a direction to move pilot valve bushing 42 downward thus cutting off the escape of oil from beneath piston 20. As long as the waste heat boiler pressure remains at a value such as to keep contact plate 81 in engagement with contacts 82, valve means 10 will be under control of contact ammeter 83, the same serving to position valve means 10 through the intermediary of pilot valve bushing 42 to maintain the load on generator 22 at the desired maximum value. Such desired maximum value may be set by adjusting load resistance 90.

In Fig. 2, I have shown an embodiment of my invention in connection with a back pressure turbine. The arrangement is substantially the same as that shown in Fig. 1 and the same reference numerals have been applied to corresponding parts. In Fig. 2, the turbine 1 supplies elastic fluid through conduit 3 for industrial purposes and it is desired to maintain in conduit 3 a certain predetermined pressure. As is well understood, the admission valve means of a back pressure turbine is operated to cause the turbine to take sufficient elastic fluid to supply through its exhaust conduit the requirements for lower pressure elastic fluid. It is required, therefore, that when the pressure in the exhaust conduit 3 decreases, indicating an increase in the demand for exhaust elastic fluid, the valve means be opened somewhat, and when the pressure in the exhaust conduit 3 increases, indicating a decrease in the demand for exhaust elastic fluid, the valve means be closed somewhat. In this arrangement, the conduit 80 connects cylinder 72 beneath piston 71 directly to exhaust conduit 3, so that piston 71 is moved in response to variations in pressure in the exhaust conduit after the same manner as variations in the pressure in header 78 moves the piston in the arrangement shown in Fig. 1. In the Fig. 2 construction, when the pressure in exhaust conduit 3 increases, piston 71 is raised somewhat thereby lowering pilot valve 60 so as to effect a closing movement of valve means 10. On the other hand, when the pressure in exhaust conduit 3 decreases, piston 71 moves downward raising pilot valve 60 to effect an opening movement of valve means 10. Thus the arrangement functions to maintain the pressure in conduit 3 substantially constant.

The magnetic fulcrum, comprising plunger 91 and winding 92, and the overload ammeter 83 operate after the same manner described in connection with the construction shown in Fig. 1. However, the contact plate 81 and contacts 82 are omitted in the Fig. 2 construction and the hand-operated switch 98 for motor 56 is arranged somewhat

differently from that shown in Fig. 1. In the Fig. 2 arrangement, hand switch 98 is utilized to operate motor 56 in either direction. When it is moved into engagement with the upper of its two contacts, motor 56 is operated in a direction to lower pilot bushing 42, thereby effecting an increase in the opening of valve means 10. It will be noted, however, that this circuit includes the contacts 85 so that an opening movement of valve means 10 can only be effected when contact arm 84 bridges contacts 85, indicating that the generator 22 is not overloaded. When either hand switch 98 is moved into engagement with its lower contact, or contact arm 84 is moved into engagement with contacts 86, motor 56 is operated in a direction to raise the pilot valve bushing 42, thereby effecting a decrease in the amount of elastic fluid supplied to the turbine. In this case, it will be noted that the circuits for the hand switch 98 and for contact arm 84 are in parallel so that they operate independently of each other, either being capable of effecting operation of motor 56. Otherwise, the arrangement shown in Fig. 2 is similar to that shown in Fig. 1 and the operation will be understood from the description already given in connection with Fig. 1.

What I claim as new and desire to secure by Letters Patent of the United States is:

1. The combination with an elastic fluid turbine having valve means for controlling the admission of elastic fluid to the turbine and means independent of said valve means for fixing the speed of the turbine, of means responsive to an operative condition other than the speed of the turbine for positioning said valve means, and means responsive to the load on the turbine for preventing said positioning means from opening the valve means to an extent such that the turbine becomes overloaded.

2. The combination with an elastic fluid turbine having valve means for controlling the admission of elastic fluid to the turbine, and a generator driven by the turbine, of means responsive to an operative condition other than the speed of the turbine for positioning said valve means, and means responsive to the load on the generator for preventing said positioning means from opening the valve means to an extent such that the generator becomes overloaded.

3. The combination with an elastic fluid turbine having valve means for controlling the admission of elastic fluid to the turbine and means independent of said valve means for fixing the speed of the turbine, of a fluid-actuated motor for moving the valve means, a speed governor-controlled pilot valve mechanism adapted to control the admission of actuating fluid to said fluid motor, a second pilot valve mechanism adapted to control the admission of actuating fluid to said fluid mo-

tor, means responsive to an operating condition other than the speed of the turbine for moving the second pilot valve mechanism, and means for rendering said last-named means inoperative whenever said turbine speed-fixing means becomes inoperative.

4. The combination with an elastic fluid turbine having valve means for controlling the admission of elastic fluid to the turbine and means independent of said valve means for fixing the speed of the turbine, of a fluid-actuated motor for moving the valve means, a speed governor-controlled pilot valve mechanism adapted to control the admission of actuating fluid to said fluid motor, a second pilot valve mechanism adapted to control the admission of actuating fluid to said fluid motor, means responsive to an operating condition other than the speed of the turbine for moving the second pilot valve mechanism, said last-named means being normally in control, and means for taking the control away from such means when the load on the turbine exceeds a certain value.

5. The combination of a turbine, an alternating current generator driven by the turbine, alternating current bus bars to which the generator is electrically connected and which serve to fix the speed of the generator and turbine, valve means for the turbine, speed governor-controlled means and means responsive to an operative condition other than the speed of the turbine for positioning said valve means, said speed governor-controlled means being normally inoperative and said other means being normally operative, and means for rendering said other means inoperative and said speed governor-controlled means operative when the generator is disconnected from said bus bars.

6. The combination of a turbine, an alternating current generator driven by the turbine, alternating current bus bars to which the generator is electrically connected and which serve to fix the speed of the generator and turbine, valve means for the turbine, speed governor controlled-means and means responsive to an operative condition other than the speed of the turbine for positioning said valve means, said speed governor-controlled means being normally inoperative and said other means being normally operative, means for rendering said other means inoperative and said speed governor-controlled means operative when the supply of current to said bus bars is interrupted.

7. The combination of a turbine, an alternating current generator driven by the turbine, alternating current bus bars to which the generator is electrically connected and which serve to fix the speed of the generator and turbine, valve means for the turbine, speed governor-controlled means responsive to an operative condition other than the

speed of the turbine for positioning said valve means, said speed governor-controlled means being normally inoperative and said other means being normally operative, and means for rendering said other means inoperative and said speed governor-controlled means operative when either the generator is disconnected from said bus bars or the supply of current to said bus bars is interrupted.

8. The combination with a turbine having valve mechanism for controlling the supply of elastic fluid thereto, of means responsive to an operative condition other than the speed of the turbine for positioning said valve mechanism, said means comprising a lever having a releasable fulcrum, a speed governor-controlled mechanism adapted to control said valve mechanism, and means responsive to an abnormal operating condition of the turbine for releasing said fulcrum whereby said first-named means is rendered inoperative and the valve mechanism is placed under control of said speed governor-controlled mechanism.

9. The combination with a turbine having valve mechanism for controlling the supply of elastic fluid thereto, of means responsive to an operative condition other than the speed of the turbine for positioning said valve mechanism, said means comprising a lever having a releasable fulcrum, a speed governor-controlled mechanism adapted to control said valve mechanism, means independent of said valve means for fixing the speed of the turbine, and means for releasing said fulcrum in case said speed-fixing means becomes inoperative whereby said first-named means becomes inoperative and the valve mechanism is placed under control of said speed governor-controlled mechanism.

10. The combination with a turbine having valve mechanism for controlling the supply of elastic fluid thereto, an alternating current dynamo-electric machine driven by the turbine, and bus bars to which the dynamo-electric machine is connected and which serve to fix the speed of the turbine, of means responsive to an operating condition other than the speed of the turbine for positioning said valve mechanism, said means comprising a lever having a releasable fulcrum, speed governor-controlled means for said valve mechanism which is normally inactive, and means for releasing said fulcrum to render said first-named means inoperative and place the valve mechanism under control of said speed governor-controlled means upon failure of the connection between the dynamo-electric machine and said bus bars.

11. The combination with an elastic fluid turbine, a generator driven by the turbine, regulating valve means for the turbine, and

- means other than a speed governor for fixing the speed of the turbine, of means for supplying elastic fluid to the turbine, means controlled by the pressure of the elastic fluid 5 for positioning said valve means whereby the turbine will be caused to utilize all the elastic fluid available from said supply means, and means responsive to the load on the generator for preventing overloading of 10 the generator.
12. The combination with an elastic fluid turbine, a generator driven by the turbine, regulating valve means for the turbine, and means other than a speed governor for fixing 15 the speed of the turbine, of means for supplying elastic fluid to the turbine, means controlled by the pressure of the elastic fluid for positioning said valve means whereby the turbine will be caused to utilize all the elastic fluid available from said supply means, and means responsive to the load on the generator which functions to prevent said pres- 20
- sure-controlled means from supplying elastic fluid to the turbine to an extent such that the generator is overloaded. 25
13. The combination with an elastic fluid turbine, a generator driven by the turbine, regulating valve means for the turbine, and means other than a speed governor for fixing the speed of the turbine, of means for supplying elastic fluid to the turbine, means controlled by the pressure of the elastic fluid for positioning said valve means whereby the turbine will be caused to utilize all the elastic fluid available from said supply means, means for rendering said pressure-controlled means ineffective in case said speed-fixing means fails, and means responsive to the load on the generator for preventing overloading of the generator. 30 35 40

In witness whereof, I have hereunto set my hand this 18th day of April, 1927.

REGINALD G. STANDERWICK.
